WITNESS:

UNITED STATES PATENT OFFICE

BASIL LESLEY LINDERSMITH, OF WILSON, OKLAHOMA

PORTABLE IRONING CABINET

Application filed March 15, 1929. Serial No. 347,354.

This invention relates to a portable ironing board cabinet, the general object of the invention being to provide a cabinet having an ironing board so arranged therein that 5 the board can be easily and quickly moved to a horizontal position and supported in said position by the cabinet, with a shelf containing part in the cabinet for holding irons and other articles and to provide the 10 cabinet with a drawer having a hinged part which, when in raised position and the drawer partly moved from the cabinet, will help to support the board in horizontal position. By making the cabinet portable, it 15 can be moved the same as any article of furniture so that the owner can take the cabinet with him when he moves from one house or apartment to another.

This invention also consists in certain 20 other features of construction and in the combination and arrangement of the several parts, to be hereinafter fully described, illustrated in the accompanying drawings and specifically pointed out in the appended 25 claim.

In describing the invention in detail, reference will be had to the accompanying drawings wherein like characters denote like or corresponding parts throughout the several views, and in which:—

Figure 1 is a front view showing the cabinet supported on a wall.

Figure 2 is a similar view but showing the doors in open position.

Figure 3 is a vertical sectional view showing the board in ironing position.

Figure 4 is a section on line 4—4 of Figure 1.

Figure 5 is a section on line 5—5 of Figure 1.

In these views, A indicates the cabinet which is provided with a bracket 1 of hinge shape at its top, whereby the cabinet can be attached to a wall or other support in such 45 a manner that the cabinet can be readily removed if the owner should desire to place the cabinet in a different position or if he should move from one house or apartment to another. The cabinet is provided with a 50 lower enlarged part 2 and a reduced upper

part 3, a top 4 being placed on the upper end of the enlarged part to form a table. A vertically arranged partition 5 is placed in the enlarged part and forms a rear chamber 6, the upper part of which is formed by 55 the reduced part 3. Shelves 7 are placed in the front chamber 8 which is formed by the partition, and each of the parts 2 and 3 has its front provided with a door 9.

A drawer 10 is arranged in the upper end 60 of the part 2 under the table 4, and the front end of this drawer is provided with a hinged extension 11 so that this extension can be swung downwardly into the drawer when the drawer is to be closed or can be swung 65 upwardly in alignment with the front of the drawer when the drawer is opened to provide a support for the ironing board 12, as hereinafter to be described. This board 12 is of such a shape that it can be placed on 70 end in the chamber 6 when not in use, as shown in full lines in Figure 2 and in dotted lines in Figure 3. When the board is to be used, it is pulled from the chamber by means of a handle forming strip 13 on its front end and its rear end placed in a slot 14 formed in the rear of the cabinet, with a portion of the board resting upon the table 4 and another portion resting upon the extension 11, so that the drawer helps to support the board. 75

A cross piece 15 is attached to the under face of the board adjacent its rear end and will abut the inner end of the table 4 when the board is in ironing position.

From the foregoing it will be seen that 85 the board can be easily and quickly pulled from the chamber and placed in horizontal or ironing position, as shown in Figure 3, and then, when the board is to be put away, it is simply necessary to pull the board slightly forwardly so that its rear end will leave the slot 14 and then the board is tilted upwardly so that it will drop into the chamber.

It is thought from the foregoing description 95 that the advantages and novel features of the invention will be readily apparent.

It is to be understood that changes may be made in the construction and in the combination and arrangement of the several 100

parts, provided that such changes fall within the scope of the appended claim.

What I claim is:—

A device of the class described comprising
5 a cabinet, means for detachably connecting
the cabinet to a support, said cabinet having
an enlarged lower part and a reduced upper
part, a table placed on the upper end of the
lower part and the rear of the cabinet having
10 a slot therein, an ironing board normally resting
in vertical position in the cabinet when
not in use, said board, when in use, having
a portion resting upon the table, with its
rear end in the slot, doors at the front of the
15 cabinet and a drawer slidably arranged in
the top part of the lower portion of the cab-
inet under the table thereof and a hinged ex-
tension on the front end of the drawer which,
when in raised position, will engage a part
20 of the under face of the board and thereby
help to support the board.

In testimony whereof I affix my signature.
BASIL LESLEY LINDERSMITH.
